UNITED STATES PATENT OFFICE.

KATHARINA SCHOLZ, OF FREIHEIT, BOHEMIA, CZECHOSLOVAKIA.

OBSTETRIC APPARATUS.

Application filed July 31, 1922. Serial No. 578,800.

To all whom it may concern:

Be it known that I, KATHARINA SCHOLZ, residing at Freiheit, Bohemia, Czechoslovakian Republic, have invented certain new and useful Improvements in Obstetric Apparatus, and for which I have filed applications in Czechoslovakia, July 2, 1921, P. 4318-21; Germany, July 7, 1921, Sch. 62269 5 11/30^e; Austria, July 4, 1921, A. 3873-21; France, July 4, 1922, No. 161,374; Belgium, July 3, 1922, No. 243,197; Switzerland, June 10 6 6, 1922, No. 18977/22, of which the following is a specification.

My invention relates to an obstetric apparatus by means of which a parturient woman may assist herself by utilizing and exerting her own muscular strength.

As is well known it is of importance to elevate the pelvis and to keep it easily accessible during the parturition as well as to provide the patient with devices which allow her to utilize her own muscular strength. Heretofore gynaecologists have attempted to accomplish these requirements by pushing cushions and the like, underneath the patient. By so doing they merely succeeded in elevating the patient's pelvis without keeping the perineum easily accessible for such manipulations or operations as might be necessary. The patient must be enabled to cling, a matter which usually is accomplished by the aid of assistants. Now the use of my apparatus hereinafter described obviates the necessity of an assistant for this purpose.

The annexed drawings show diagrammatically two arrangements for practicing my invention.

Fig. 1 relates to a parturient keeping a stretched posture and shows a bed in cross-section.

Fig. 2 is a side elevation of Fig. 1.

Fig. 3 shows a transverse cross section of a bed showing the apparatus attached entirely to one side of the bed.

The apparatus as shown in Figs. 1 and 2 is attached to both sides of the bed consists of a saddle *e* which is pushed under the pelvis of the patient and is connected at its ends to a line, rope or other flexible element *k* which passes around a roller *g* carried by the supports *i* which are securely fixed to the bedsides.

These supports are preferably secured to the sideboards of the bed by means of the two clamps *n* which are adapted to overlap

the edges of the sideboards and are secured together in vertically spaced relationship by means of a strut *m* in which the clamps are adjustably screwed so that they may be adjusted according to the height of the sideboards of the bed.

If the apparatus is used on a metal bed an adjustable reinforcing strut *l* is inserted between the metal tubes of the bed (as shown at the right of Fig. 1). The strut *m* is provided with a bearing *m'* in which a sheave *f* is rotatably mounted and which can be operated by a lever *h* rigidly attached thereto. The line *k* which runs round the roller *g* is fixed in a groove of said sheave *f* so that, when the lever *h* is forced down, the movement of the sheave will cause the line to pull upon the saddle and elevate it.

If the patient is placed in the stretched posture the apparatus is fixed to the two bedsides so that the supports are connected with each other by the saddle *e*.

By grasping the handles of the levers *h* on either side and forcing them down the patient brings herself into the required position which can be even improved by an assistant further depressing the lever. The handle *c* is then screwed on the support *i* so that the patient is enabled to firmly cling with thrown out arms. The release lever *h* is prevented from returning to its original position by means of the pawl and ratchet *p* so that any change of the elevated posture of the patient is avoided. Supports for the patient's feet are provided by the upper faces of the sideboards of the bed. The clinging on the handles of the supports *i*, which are placed outside the surgeon's sphere of action, as well as the pressure of the feet against the sides of the bed enables the necessary muscular effort of the patient needed for a proper confinement to be properly exerted.

If it is desired to keep the patient in a slanting position, both of the struts *i* and the parts attached thereto are secured to only one side of the bed (as shown in Fig. 3) and the patient is placed transversely across the bed. When the apparatus is used in this manner the foot rests *d* in which the patient's feet may be placed are placed upon the levers *h* and the handles *c* are placed on the supports *i*, the patient causing the saddle *e* to be raised by forcing downwardly against the foot rests in a manner which will be obvious.

- It may be pointed out as an advantage of this arrangement which is used merely in precarious cases, that it makes the pelvis of the patient quite easily accessible so that the surgeon is enabled to perform any necessary operation and also that the supports against which the strength of the patient is exerted do not interfere with the sphere of action of the physician.
- 10 The several parts of the apparatus are quite foldable and manageable so that the apparatus is easily transportable and can be attached to any bed.

Having now particularly described my invention and what it consists of I declare that what I claim is:

1. An obstetric apparatus for facilitating parturienty comprising a pair of supports, sheaves rotatably mounted on said supports, a vertically movable saddle upon which the pelvis of the patient is adapted to be supported, a lever rotatably mounted on each support, a handle adapted to be interchangeably secured to said support or said lever and flexible means connecting said lever and saddle and passing over said sheaves, whereby when the muscular strength of said pa-

tient is exerted upon said lever said saddle will be raised.

2. An obstetric apparatus as set forth in claim 1 in which a pawl and ratchet is connected with said lever to automatically lock said lever and hold said saddle in its raised position.

3. An obstetric apparatus for facilitating parturienty comprising a pair of supports, sheaves rotatably mounted on said supports, a vertically movable saddle upon which the pelvis of the patient is adapted to be supported, a lever rotatably mounted on each support, a handle adapted to be detachably secured to said support or said lever, flexible means passing over said sheaves connecting said lever and saddle and a foot rest adapted to be detachably secured to said lever whereby said lever may be actuated by the muscular strength of the arms or legs of the patient to raise said saddle.

In testimony whereof I affix my signature in presence of two witnesses.

KATHARINA SCHOLZ.
